UNITED STATES PATENT OFFICE.

OSCAR JUNGGREN, OF SCHENECTADY, NEW YORK, ASSIGNOR TO GENERAL ELECTRIC COMPANY, A CORPORATION OF NEW YORK.

ELASTIC-FLUID TURBINE.

No. 873,051.

Specification of Letters Patent.

Patented Dec. 10, 1907.

Application filed April 8, 1905. Serial No. 254,517.

To all whom it may concern:

Be it known that I, OSCAR JUNGGREN, a citizen of the United States, residing at Schenectady, county of Schenectady, State of New York, have invented certain new and useful Improvements in Governing Mechanism for Elastic-Fluid Turbines, of which the following is a specification.

In the construction of certain types of multistage elastic-fluid turbines, separately actuated valves under the control of a suitable speed or load-responsive device are provided for regulating the admission of motive fluid to the first stage, and independent and separately actuated stage valves between two, three or more of the subsequent stages of lower pressure for regulating the passage of fluid through some or all of the stage nozzles. The stage valves are constructed and arranged to be opened and closed by changes in stage pressures, the object being to maintain constant or substantially constant pressures in the different stages.

My present invention has for its object to attain the advantages of the arrangement referred to above by a simpler construction.

In carrying out my invention, a suitable number of nozzles are provided for the first stage, the number depending upon a certain predetermined load. The pressure on the first stage casing is determined by the amount of steam or other elastic fluid passing through it. The succeeding stages are each provided with main stage nozzles of sufficient cross-sectional area to handle the volume of steam or other elastic-fluid at the pressures existing in the stages, and may be expanding or non-expanding in character. The admission nozzles may each be provided with a nozzle valve which opens and closes in response to load changes, or one valve may control two or more nozzles or nozzle sections, the latter being preferably closely associated so as to discharge an unbroken column of fluid against the wheel buckets. The valves preferably, but not necessarily, have an open and a closed position but no intermediate, and may be operated directly or indirectly by electro-magnetic means, by mechanical means, by fluid pressure means, or by a combination of said means, as desired. I may also provide the main stage nozzles previously referred to with valves of a similar or different type to the admission valves

and control them in the same or in a different way. Except where great refinement in regulation is required, valves for the main stage nozzles will not ordinarily be necessary.

Thus far the construction is the same as that disclosed in applications previously filed by me.

Stated generally, my improvement over said applications consists in admitting live steam or other motive fluid under pressure directly to the second stage or to a subsequent stage or to both the second and one or more of the subsequent stages, through suitably designed nozzles, the said nozzles having a different ratio of expansion from the other nozzles in the stage or stages. By reason of this construction I am able to dispense with the automatic pressure-actuated stage valves and thus improve and simplify the apparatus.

In addition to the main stage nozzles referred to are other stage nozzles which to distinguish them will be termed "auxiliary stage nozzles", to which steam or other fluid at boiler pressure or pressure considerably above a given stage is admitted. These auxiliary nozzles, instead of being in open communication with the different stages, are closed thereto and only receive their fluid from a source of higher pressure. As a simple way of accomplishing this the auxiliary nozzles receive fluid from passages formed in the casing or from conduits extending from the supply chest containing the admission valves. The motive fluid may however, be received from a separate source of supply if desired. Many arrangements can be provided for this purpose, so the invention is not to be construed as being limited to the specific construction illustrated. The passage of motive fluid to the auxiliary stage nozzles is controlled by a suitable valve mechanism. I prefer to employ individual and successively operated valves for this purpose responding to changes in load on the turbine, but the invention is not limited in all respects to this arrangement. In order to simplify the construction, the admission and stage valves are controlled by the same shaft governor.

The idea of employing admission and stage valves responsive to a governor which control the admission of live steam to the high as well as the low pressure stages of the

turbine, in connection with the proper nozzles, I regard as an important feature of my invention. By reason of this arrangement the valves will quickly respond to load changes 5 and there will be no lag such as is the case with pressure actuated devices.

Since the pressure of the fluid passing through the auxiliary stage nozzles is higher than that passing through the main stage 10 nozzles, it follows that the ratio of expansion of the auxiliary nozzles must be greater than that of the main nozzles. This means that one set of stage nozzles is discharging motive fluid at one velocity and other nozzles in the 15 same stage at a different velocity, the fluid from both sets of nozzles acting on the same wheel buckets. The pressure of the fluid stream issuing from the auxiliary stage nozzles should be the same or approximately 20 the same as that of the receiving stage. The turbine is so governed that the bucket speed is correct for the motive fluid issuing from the main stage nozzles or nozzle sections and is therefore somewhat low for the motive 25 fluid issuing from the auxiliary stage nozzle or nozzles or nozzle sections. In other words, the residual velocity of the motive fluid from the auxiliary stage nozzle or nozzles is in excess of that from the main 30 stage nozzles. This excess velocity is reconverted into heat upon being suddenly brought to rest by the wall or other part of the wheel casing which increases the temperature of the motive fluid in the stage and 35 also serves to reëvaporate some or all of the moisture in the stage. This action may be repeated in one or more of the subsequent stages, the same general arrangement of parts being provided. From this it follows 40 that whatever energy may be lost in one stage is available in the subsequent stage or stages, because the fluid is renozzled in passing from one to the other.

The admission nozzles are preferably so 45 constructed and designed that the work done in the first stage at normal load is greater than that done by any subsequent stage under said condition. Preferably the pressure in the first stage should not exceed fifty- 50 eight per cent. of the boiler pressure when the maximum amount of motive fluid is flowing through the machine, since otherwise it would reduce the flow of steam through the admission nozzles and thus decrease the 55 effectiveness of the first stage.

The present arrangement is exceedingly flexible in that it can be adapted for use with machines differing greatly in capacity and for wide ranges in load. With different 60 chines the expansion ratios of the nozzles would ordinarily be changed to suit the conditions of operation. The turbine illustrated is intended to operate at its rated full load capacity without the auxiliary stage 65 nozzles being in service and to have an over-

load capacity of one hundred per cent. If the turbine is rated to give its maximum output with all nozzles in service, then the auxiliary stage nozzles will start into operation at about half load. It is preferable to rate 70 a turbine rather low in order that it may handle anything within reason in the form of an overload.

By increasing the number of auxiliary stage nozzles, the pressure in the different 75 stages can be kept more nearly constant under load changes, but since an increase in number tends toward complication and increased cost of maintenance, it is desirable to use as few as possible.

Nothing in this specification is to be construed as limiting the invention to any specific number of auxiliary stage nozzles in a given stage or to the number of stages in the machine which are so provided nor to the 80 number of valves under the control of a suitable controlling mechanism for regulating the passage of fluid through said nozzles, since different conditions require somewhat 85 different arrangements. The controlling 90 valves for the auxiliary nozzles may be located in the same chest with the admission valves or they may be located in one or more separate chests. The use of a single chest with duplicate valves is desirable on account 95 of simplicity in construction. Concentrating the admission and stage valves in the same place render it easier for the attendant to inspect them from time to time to see if they are working properly. It also simplifies the construction of the turbine as a 100 whole.

By causing the live steam admitted to the low pressure stages to first pass through one or more nozzles having the proper ratio of expansion I am able to obtain substantially the full benefit of the expansion due to the difference in pressure. On the other hand if the steam was discharged directly into a low pressure stage and there permitted to mix 110 with the main body of steam, the effect of the expansion from the high to the low pressure would be lost. Moreover this would have the effect of backing up the pressures in the higher pressure stages which should be avoided 115 as far as possible.

My invention can be used in connection with high-pressure turbines, or with low-pressure turbines receiving the exhaust from reciprocating engines, turbines or other 120 source of supply.

In the accompanying drawings which illustrate embodiments of my invention, Figure 1 is a view in elevation, with certain of the parts broken away, of a vertical-shaft turbine; 125 Fig. 2 is a view in side elevation, with certain of the parts broken away, of a horizontal turbine; Fig. 3 is a view in end elevation of the machine shown in Fig. 2, with parts of the valve chest broken away for the purpose. 130

of illustration; Fig. 4 is a detail view showing a passage from the source of supply to the auxiliary stage nozzle cored out of the casing, as distinguished from a conduit located entirely outside of the casing; Fig. 5 is a longitudinal section of the valve chest; Fig. 6 is a vertical axial section through the turbine casing showing the chambers for collecting the water; Fig. 7 is a horizontal section of the same showing the controlling valve; Fig. 8 is a cross section of the controlling valve; and Fig. 9 is a diagrammatic view of one of the auxiliary nozzles having an exaggerated expansion for the purpose of illustration.

15 The invention is shown in connection with a turbine of the Curtis type, but it is also applicable to other types of machine operating on the impact principle.

1 represents the base of the machine which 20 is connected to a condenser or other exhaust by the neck 2. Located within the base is a suitable step bearing (not shown) for supporting the weight of the moving parts. Mounted on top of the base is a casing 3 containing two or more wheels 4. The wheels 25 of one stage are separated from those of another stage by diaphragms 5 which are supported by suitable internal shoulders formed on the casing. In the present illustration each stage is provided with two rows of wheel buckets 6 with intermediate buckets 7 located between them and in line with the nozzles. I may employ one, two or more rows of wheel buckets per stage depending 30 upon the conditions of operation. Steam or other elastic fluid is admitted to the turbine by one or more nozzles 8. These nozzles are preferably composed of a plurality of closely associated expanding passages 9 which convert the pressure of the motive fluid into 35 velocity and discharge it against the adjacent wheel buckets, the intermediate buckets 7 serving to reverse the direction of the motive fluid as it passes from one row of wheel buckets to the other. The nozzles between stages 40 are similar in construction to the admission nozzle or nozzles 8 except that they are somewhat larger in cross section to accommodate the increased volume of steam. They may, however, be non-expanding in character, or 45 they may differ slightly as to their expansion ratio where the machine is intended to develop unequal work per stage as in the present instance. The casing of the machine is provided 50 with a head or cover 10 upon which rests the stool 11 that supports the generator where the turbine is employed for driving such a machine.

55 Mounted on top of the head of the machine is a valve chest 12 containing a plurality of individual and successively operating valves, which valves have an open and a closed position but no intermediate to prevent throttling of the motive fluid as it passes to the nozzles. As shown three valves

13 are provided for regulating the admission of elastic fluid to the admission nozzles of the first stage, each valve being arranged to control the supply of two nozzle sections. Each of these valves is actuated by a piston 14, 70 and the latter is controlled by a relay valve in response to movements of the armature 15 of an electro-magnet. The electro-magnets are provided with suitable pole-pieces 16 and the circuits of the magnets are controlled by 75 a contact cylinder 17 or other device for making and breaking their circuits. The current for energizing the magnets is received from a generator or other source of supply 18. The contact cylinder is provided with a pinion on the end of its supporting shaft, which meshes with a rack 19, the latter being connected to the lever 20. This lever is suitably pivoted and is actuated by a speed-responsive device 21 which is shown 80 diagrammatically for the purpose of illustration. This speed governor may be actuated directly by the speed of the turbine shaft, or it may be driven from a countershaft as desired.

90 In addition to the main stage nozzles are auxiliary stage nozzles 22 which comprise one or more sections, each of which has a greater expansion ratio than the main stage nozzles owing to the fact that they receive 95 motive fluid at considerably higher pressure. These nozzles can with advantage be formed in or connected to the diaphragms 5. The wall of the casing 3 is cored out at 23 to form a passage for discharging fluid to the nozzles. 100 In the present illustration elastic fluid is supplied to the nozzles by external conduits 24 and 25 which are connected at one end to the valve chest 12 and at the other end are screw-threaded into the wheel casing 3 in line with 105 the openings 23. On the left hand side of Fig. 1 the conduit 24 is shown as discharging into an auxiliary stage nozzle discharging into the second stages. On the right-hand side of Fig. 1 the conduit 25 is shown as receiving steam or other elastic fluid from the valve chest 12 and discharging it into a nozzle or nozzles discharging into the third stages, the said machine being of the four-stage type. Admission of fluid to the auxiliary stage nozzles is controlled by valves 110 115 26 and 27 which are similar in construction and operation to the nozzle valves 13.

120 From the foregoing it is apparent that since the auxiliary stage nozzles receive motive fluid from the same source of supply as the admission nozzles, their ratio of expansion must be greater, so that the fluid discharged therefrom will have the same or substantially the same pressure as that of the 125 receiving stage. It is also obvious that the expansion of the nozzle or nozzles discharging into the third stage should be greater than that of the nozzle or nozzles discharging into the second stage, because the pressure 130

in the third stage is considerably lower than that in the second stage.

The governing mechanism is so constructed and arranged that the admission valves 13 are opened one after the other as the load increases, then the valve 26 is opened and finally the valve 27. When the valves 13 are open the machine will be operating at its normal rated capacity, and when the valve 26 is open it will be operating at 50 per cent. overload; and when the valve 27 is open the machine will be operating at 100 per cent. overload. It is to be noted that these statements are based upon the proposition that the normal full load rating of the machine is one half the total capacity of the machine.

Referring to Fig. 2 I have shown my invention applied to a six-stage horizontal machine wherein each stage is provided with two rows of wheel buckets. This machine is so constructed and arranged that the first stage will perform a greater amount of work than any of the subsequent stages, and furthermore the parts are so designed that the pressure in the first stage, even when under maximum load conditions, does not exceed 58 per cent. of the initial or boiler pressure in order to prevent a decrease in the flow of motive fluid from the admission nozzles under maximum load conditions. In other words, the pressure in the first stage should be such that even though double the amount of steam required for normal load conditions be discharged through the machine, the pressure in the first stage will never be more than 58 per cent. of the initial pressure. When this condition is observed the flow of steam through the admission nozzles will not be reduced, even though the load on the machine be varied from normal to 100 per cent. overload. For example, assuming that the machine is intended to handle 235,000 foot pounds of energy per unit of time, then the first stage may be designed to handle 65,000 foot pounds of energy and each of the remaining stages 34,000 foot pounds of energy per unit of time. This means that the expansion ratio of the admission nozzles is greater than the expansion ratio of the main stage nozzles. For example, the admission nozzles may be arranged to discharge motive fluid at 2050 feet per second while the normal stage nozzles discharge fluid at 1480 feet per second, the boiler pressure being 165 pounds absolute.

I do not wish to be understood as limiting myself to the figures above set forth because the expansion ratio of the nozzles and the conditions of operation can be widely varied without departing from the spirit of my invention.

Under the conditions of operation set forth above, there will be a difference in stage pressure between the full load and overload condition, but this variation in pressure can

be maintained within certain prescribed limits. These limits may be small or comparatively large, depending upon the prescribed conditions of operation.

30 represents the main shaft of the turbine upon which are mounted bucket-carrying wheels 31. In the present instance six of these wheels are provided, all of which are similar in construction. Each wheel is provided with two rows of buckets 32 for fractionally abstracting the velocity of the motive fluid. Located between the rows of wheel buckets are intermediate buckets 33 which serve to reverse the direction of the motive fluid and properly discharge it against the adjacent buckets. The buckets are inclosed within a casing 34 made up of suitable sections which are bolted or otherwise secured together. The fluid exhausts from the machine by the conduit 35. The valve chest 36 is bolted to the head 37 of the machine and is provided with a conduit 38 for admitting steam or other elastic fluid. The admission nozzles 39 to the first stage are of the construction described in connection with Fig. 1, and are bolted to the head 37 of the machine. The admission of motive fluid to the nozzles is controlled by separately actuated valves as previously described. Elastic fluid from the valve chest is supplied to the auxiliary stage nozzles discharging into the second stage by the conduit 40, and motive fluid is admitted to the nozzles discharging fluid into the third or subsequent stage by the conduit 41 located on the opposite side of the machine. These conduits are best shown in Fig. 3. The construction of the nozzles may be the same as that previously described.

In Fig. 4 is shown a construction wherein the conduits or passages 42 which discharge live steam or other motive fluid to the auxiliary stage nozzles 43 are cored out of the wheel casing and are thus located entirely within the machine as distinguished from having external conduits as shown in the previous figures. 44 represents a valve for controlling the admission of fluid to the auxiliary nozzle discharging into the second stage. This valve is arranged to have an open and a closed position but no intermediate, and is responsive to speed changes.

In Fig. 5 is shown a longitudinal section of the valve chest referred to in connection with Fig. 4. 45 represents the admission valves controlling the admission of fluid to the first stage and 44 and 46 represent the valves controlling the admission of fluid to the auxiliary stage nozzles. The conduits 42 and 47 shown in dotted lines convey motive fluid from the valves 44 and 46 to the auxiliary stage nozzles.

To the under side of the wheel casing, (Figs. 2, 3, 6 and 7), is bolted a casing 48 which is divided into compartments 49 by

the walls 50. These compartments are individually connected to the different stages with the exception of the last which is piped direct to the condenser. Communication between the compartments is accomplished by passages 51, Fig. 7. Situated within the casing 48 and extending parallel with the base of the machine is a valve 52. This valve contains passages registering with passages 51 and when located in one position the water due to expansion and condensation can be blown from one stage to another. When rotated to its other position the valve closes all of the passages. At the right hand end of the casing 48 is a discharge pipe 53 which is connected to the condenser when the machine is operating condensing and to a suitable exhaust when the turbine is intended for non-condensing service. Located in the pipe is a manually actuated valve 54 for controlling the passage of water through it.

In Fig. 9 is shown one of the auxiliary stage nozzles 43 of Fig. 4 on an enlarged scale, the ratio of expansion between the throat 56 and the discharge end 57 being exaggerated for the purpose of illustration. In order that the difference in expansion between the main and auxiliary stage nozzles 30 may be clearly seen, I have shown in dotted lines 58 the opposed walls of one of the main stage nozzles.

Instead of locating the wheels within a casing made in a single structure with dia-

phragms or partitions between, the wheels may be located in a casing composed of separate units with suitable connecting passages.

My invention is also applicable to impact turbines where the direction of flow is radial, and to turbines where the flow is both radial and axial. In general it may be stated that the direction of flow through the machine may be in any desired direction.

I have described a type of valve mechanism which has been found to be satisfactory, but I do not wish to be understood as being limited thereto, for the reason that other forms of governing mechanism may be used.

In accordance with the provisions of the patent statutes, I have described the principle of operation of my invention, together with the apparatus which I now consider to represent the best embodiment thereof; but I desire to have it understood that the apparatus shown is only illustrative and that the invention can be carried out by other means.

What I claim as new and desire to secure by Letters Patent of the United States, is:

1. In a turbine wherein the pressure of the motive fluid is converted into velocity and the energy abstracted by successive stages, the combination of nozzles and wheel buckets arranged in stages, and an auxiliary stage nozzle or nozzle sections which receive and

convert motive fluid of higher pressure than the main stage nozzles into velocity and discharge it against the wheel buckets.

2. An elastic-fluid turbine wherein the pressure of the motive fluid is converted into velocity and the energy abstracted by successive stages, comprising admission and main stage nozzles, and wheel buckets for abstracting the velocity from the motive fluid, in combination with one or more auxiliary stage nozzles which receive motive fluid under higher pressure and have a greater ratio of expansion than the main stage nozzles and discharge it against the wheel buckets.

3. An elastic-fluid turbine wherein the pressure of the motive fluid is converted into velocity and the energy abstracted by successive stages, comprising admission and main stage nozzles, wheel buckets for abstracting the velocity from the motive fluid, and a chest from which the admission nozzle or nozzles receive their supply of motive fluid, in combination with one or more auxiliary nozzles discharging into a low pressure stage which receive motive fluid from the chest and discharge it against the buckets, the said auxiliary stage nozzle or nozzles having a greater ratio of expansion than the main stage nozzles.

4. In an elastic-fluid turbine wherein the pressure of the motive fluid is converted into velocity and the energy abstracted by successive stages, the combination of wheel buckets, a nozzle for converting the pressure of motive fluid into velocity and discharging it against the buckets, a second nozzle having a greater ratio of expansion than the first which also discharges motive fluid against the same buckets, and means for rendering one nozzle active for certain load conditions, and for rendering both nozzles active for greater load conditions.

5. In an elastic-fluid turbine, the combination of two or more bucket wheels, a separate compartment for each wheel, admission nozzles for the first stage, nozzles between stages which convert a certain amount of the pressure of the motive fluid in the first stage into velocity and discharge it against the wheel buckets of the second stage, and one or more auxiliary stage nozzles which receive motive fluid under a pressure exceeding that in the first stage and after converting it into velocity discharge it against the wheel buckets of the second stage at a pressure the same or substantially the same as that existing in said second stage.

6. An elastic-fluid turbine wherein the pressure of the motive fluid is converted into velocity and the energy abstracted by successive stages, comprising admission and main stage nozzles and wheel buckets for abstracting the velocity from the motive fluid, in combination with auxiliary stage nozzles

which discharge motive fluid against the wheel buckets of a low pressure stage or stages at a velocity greater than that due to the main stage nozzles, and a source of elastic fluid for the auxiliary stage nozzles the pressure of which exceeds the pressure of the fluid in the stages.

7. In an elastic-fluid turbine wherein the pressure of the motive fluid is converted into velocity and the energy abstracted by successive stages, the combination of wheel buckets and nozzles arranged in stages for handling the load on the machine up to a certain point, means for carrying motive fluid around a high-pressure stage when the load increases above said point, and auxiliary stage nozzles which are cut off from the other nozzles and discharge motive fluid received from said means against the wheel buckets.

8. In an elastic-fluid turbine wherein the pressure of the motive fluid is converted into velocity and the energy abstracted by successive stages, the combination of wheel buckets arranged in separate compartments, nozzles between stages which are always open thereto, one or more auxiliary stage nozzles which are closed against the entrance of motive fluid from the stages, means for supplying motive fluid directly from a source of supply to the auxiliary stage nozzles, and valve mechanism for governing the admission of fluid to the auxiliary nozzle or nozzles.

35 9. An elastic-fluid turbine in which the pressure of the motive fluid is converted into velocity and the energy abstracted by successive stages, comprising admission and main stage nozzles, with wheel buckets located adjacent to the nozzles and acted upon by the fluid therefrom, the said wheel buckets being arranged in separate stages or compartments, in combination with auxiliary stage nozzles for one or more of the low pressure stages having an expansion ratio greater than that of the main stage nozzles, valve mechanism for controlling the admission of high-pressure motive fluid to the admission nozzles for certain load conditions and to the admission and auxiliary stage nozzles for other load conditions, and a device responding to load conditions for actuating the valve mechanism.

55 10. In an elastic-fluid turbine, the combination of a plurality of rows of wheel buckets for abstracting the velocity of the motive fluid, means for separating the wheel casing into separate compartments, nozzles for admitting fluid to the first stage, main stage nozzles which convey fluid from one stage to the next, auxiliary stage nozzles which are cut off from the main stage nozzles and have a greater ratio of expansion, the said main and auxiliary stage nozzles co-operating to

mon to the admission nozzles and to the auxiliary stage nozzles, a plurality of valves located in the chest for controlling the passage of motive fluid therefrom, and a means for successively actuating the said valves.

70 11. In an elastic-fluid turbine, the combination of a casing divided into stages or compartments, rows of wheel buckets in each stage for abstracting the velocity of the motive fluid by successive fractions, admission nozzles, main stage nozzles located between wheel compartments, auxiliary stage nozzles acting upon an increase in load to discharge motive fluid under high velocity to the low-pressure stage buckets, and a valve mechanism and speed-responsive device which are common to the admission and auxiliary stage nozzles.

75 12. In an elastic-fluid turbine, the combination of a plurality of rows of wheel buckets arranged in separate compartments or stages, main stage nozzles receiving fluid from one stage and discharging it into another, a supply chest, nozzles receiving fluid from the chest and discharging it into one stage, auxiliary stage nozzles which are cut off from the main stage nozzles and have a different ratio of expansion, and conduits extending from the source of supply which shunt one or more stages and discharge motive fluid at high pressure to the auxiliary stage nozzles.

80 13. In an elastic-fluid turbine, the combination of a plurality of stages, each stage being provided with suitable nozzles and wheel buckets, with auxiliary stage nozzles acting under certain load conditions to augment the effect of the main stage nozzles, the said auxiliary nozzles receiving motive fluid at a pressure above that of the main stage nozzles and having a greater ratio of expansion.

85 14. In an elastic-fluid turbine, the combination of a casing which is divided into stages, bucket wheels for the stages, main stage nozzles between the stages, the nozzle or nozzles leading into the first stage and those between the first and second being so constructed and arranged that the pressure in the first stage does not exceed 58 per cent. of the initial pressure, and an auxiliary stage nozzle for one of the stages, which has a greater expansion ratio than the main stage nozzle or nozzles discharging into said stage.

90 15. In an elastic-fluid turbine, the combination of a casing divided into compartments, bucket wheels therein, admission and main and auxiliary stage nozzles which discharge motive fluid against the buckets to produce rotation, the main and auxiliary stage nozzles having different ratios of expansion, a valve mechanism which controls the admission of live motive fluid to the admission and also to the auxiliary stage nozzles, and a speed responsive device controlling the action of the valve mechanism.

76

75

100

105

110

115

120

125

130

16. In an elastic-fluid turbine, the combination of a plurality of stages, each stage being provided with suitable nozzles and wheel buckets, auxiliary stage nozzles for stages of successively decreasing pressure which directly discharge fluid against the wheel buckets, the ratio of expansion of the auxiliary stage nozzles successively increasing toward the exhaust and being greater in each instance than that of the main nozzles in said stage, and means for controlling the passage of high pressure motive fluid to the auxiliary stage nozzles.

17. An elastic fluid turbine, comprising a plurality of stages, fluid discharging devices and wheel buckets for the stages, the said devices in the first stage producing a greater drop in pressure than those of the succeeding stages, in combination with auxiliary stage nozzles which have a greater expansion ratio than the main stage nozzles, and conduits for supplying motive fluid thereto.

18. An elastic fluid turbine, comprising a plurality of stages, fluid discharging devices and wheel buckets for the stages, the said devices in the first stage producing a greater drop in pressure than those of the succeeding stages, in combination with auxiliary stage nozzles which are prevented from receiving motive fluid from the preceding stage, and valve controlled means for supplying motive fluid to these nozzles at a pressure above that of the preceding stage, the main stage nozzles receiving fluid at the pressure of said preceding stage.

19. An elastic fluid turbine, comprising a plurality of stages, fluid discharging devices

and wheel buckets for the stages, the said devices and wheel buckets of the first stage being constructed to develop a greater 40 amount of work for a given supply of fluid than those of a subsequent stage, an auxiliary stage nozzle, a conduit for supplying high pressure fluid thereto, and a governor controlled valve for regulating the passage of 45 fluid through the conduit.

20. In an elastic-fluid turbine, the combination of a casing which is divided into compartments, wheels in said compartments, passages leading from one compartment to 50 another through which the water due to expansion and condensation may pass, and a valve which is common to said passages.

21. In an elastic fluid turbine wherein the pressure of the motive fluid is converted into 55 velocity and the energy abstracted by successive stages, the combination of wheel buckets arranged in the separate stage compartments, fluid-discharging devices between the stage compartments which are always 60 open thereto, one or more auxiliary stage fluid discharging devices which discharge fluid directly to wheel buckets and are closed against receiving motive fluid from the stages, and a conduit for supplying motive 65 fluid to the said auxiliary discharging device or devices.

In witness whereof I have hereunto set my hand this 7th day of April, 1905.

OSCAR JUNGGREN.
